DESIGN FOR A DESK UNIT

Bailey T. Bowers, Chicago, Ill.

Application May 27, 1947, Serial No. 139,301

Term of patent 14 years

(Cl. D74—1)

To all whom it may concern:

Be it known that I, Bailey T. Bowers, a citizen of the United States and a resident of Chicago, in the county of Cook and State of Illinois, have invented a new, original, and ornamental Design for a Desk Unit, of which the following is a specification, reference being had to the accompanying drawing, forming a part hereof.

I claim:

The ornamental design for a desk unit, substantially as shown.

BAILEY T. BOWERS.
